DEEP WELL PUMP

Julius Paul, Duluth, Minn., assignor of one-half
to R. M. Sellwood, Duluth, Minn.

Application December 21, 1936, Serial No. 116,946

6 Claims. (Cl. 103—9)

This invention relates to double acting deep well fluid operated pumps, the principal object being to provide a more practical, simple and durable pump, efficiently and dependably operable at great depths, especially in the art of oil pumping.

Another object is to provide such a pump which will effectively care for air or gas encountered within such pumping operations.

10 Still other objects and advantages of the invention will appear in the following description thereof.

Referring now to the accompanying drawings, forming part of this application, and wherein 15 like reference characters indicate like parts:

Figure 1 is a broken central vertical section on the line 1—1 of Figures 2 and 3 showing a pump unit within a common oil well casing, except that the showing of the rotative twin gate valve is 20 on the line 1—1 of Figure 4 for a better comprehension of the registration of the various ports during the operation of the device subsequently set forth. The figure is a somewhat unusual showing in that the horizontal dimensions are 25 approximately one-half full size whereas the vertical dimensions of the pump unit are materially foreshortened so that the entire structure may be illustrated in one figure.

Figures 2, 3, 4, 5, 6, 7, 8, 9, and 10, are transverse 30 sections respectively on the lines 2—2, 3—3, 4—4, 5—5, 6—6, 7—7, 8—8, 9—9, and 10—10, Figure 1.

In Figure 1 there is a further modification 35 from the usual representation of a practical embodiment of the invention, in that the parts of the motor and pump illustrated as integral are cross hatched with alternate full and dotted lines so that these simultaneously movable parts are more readily comprehensible.

40 1 represents the casing of an ordinary oil well, the portion thereof here illustrated being that found adjacent the bottom of the well and within the oil therein, 2 represents the pump cylinder within the casing, the lower end of which cylinder is attached to an ordinary packer, illustrated at O, within the casing, and the extreme lower end of the pump suction pipe 82 is normally reciprocable within the oil in the well. The upper portion of this cylinder is provided centrally 45 thereof with the externally screw threaded connection 3, to which is attached the power supply line not shown of the pump. Upon opposite sides of this central connection 3 are illustrated connections for two standpipes 4 and 5, extending to 50 the surface of the well, and the former being for

the care of gas delivered by the pump and the latter for service solely as a standpipe in insuring uniformity of pressure in the pump and provided with a suitable adjustable safety valve, not shown, to control the working pressure of the power fluid. The connection, above the motor of the pump, to the gas standpipe 4 comprises an axially disposed depending nipple 6 within which is reciprocably mounted the uppermost end of the hollow piston stem 7, about which may be fixed any number of stuffing glands, one of which is suggested at 8 to insure against undue leakage. Externally of this nipple section 6 is a somewhat reduced portion 9 of the pump cylinder forming a chamber 10 intermediate of the nipple 6 and about same internally of the upper end of the pump cylinder, and which chamber also communicates as by the passageway 11 with the standpipe 5. Within this reduced portion 9 of the pump cylinder is mounted the vertically intermittently reciprocal cylindrical valve 12, having the annular port or passageway 13 thereabouts, it being the exhaust port of the pump control valve. This valve cylinder is provided with the power supply ports 14 and 15 upon opposite sides thereof, and which ports respectively register alternately with the passageways 16 and 17, their relative position with the gate valve 20 being shown in dotted lines, Fig. 3. The valve 12 in its present position is shown as supplying power through the port 14 to the passageway 16, while the passageway 17 is communicating through the exhaust port 13 and discharging out of the port 18 in the wall of the reduced portion 9 of the pump cylinder; the arrows in the drawings indicating such action. This position of the valve is that just prior to its being drawn to its extreme lowermost position by continued action of the motor piston which will be described later. In its present position the valve 12 as is obvious will have permitted power fluid to have coursed the passageway 16 into the annular chamber 19 in which is installed the swingable gate valve 20, and will have obviously swung this gate valve anti-clockwise as viewed in Fig. 3 of the drawings, simultaneously turning the cylindrical valve stem 21 to the position illustrated in Figs. 3 and 4 of the drawings. The limit of throw of the gate valve 20 in either direction is governed by the arcuate projections 85 of the block 86 fixed within the opposite side of the chamber 19. This hollow cylindrical valve stem 21 carries radially disposed upon its lowermost extremity the twin gate valve member 22 operable swingably within the annular chamber 23 of the pump cylinder, it

being noted that about the enlarged central portion of the hollow valve stem 21 is installed a suitable ball bearing 24 upon which rests the combined block and floor member 86, the floor 5 portion 25 forming the bottom of the chamber 19 in which the gate valve 20 operates. Also at the lower end of this hollow valve stem 21 is a second ball bearing 26 to insure as nearly as possible non-frictional action of the rotation of this hollow 10 valve stem 21.

It will be noted that the twin gate valve 22 is provided with a passageway 27 between the two lateral terminals thereof which at all times is in direct communication with the central power 15 passageway indicated at 28 in the various views so that power fluid is always available therein, and while the passageway 27 is communicating through the port 29 to the vertical semi-annular passageway 30 in one side wall of the pump, it 20 will be furnishing power directly against the uppermost end of the motor piston 31, and, as before stated, will, when in the position illustrated and power is further applied, force the motor piston to its final lowermost position which 25 will complete the downward stroke of the control valve 12 by action of the ring 32 fixed about the piston stem 7 engaging the finger-like member 33 formed integral with the bottom of the valve 12, and extending radially inwardly and 30 about the stem 7 as more clearly shown in Fig. 2 of the drawings. At this change of the port communications of the valve 12, it will be noted that instantly power fluid from the interior of said valve will pass through the port 15 and passageway 17 to that portion of the chamber 19 upon the opposite side of the gate valve 20, and instantly reverse its position, to that indicated by the dotted line 34, Fig. 3, from that previously described, simultaneously rotating the twin gate valve 22 to its opposite position, as indicated by the dotted line 35, Fig. 4, which controls the opposite line of communication to the motor piston just described, thus opening up communication for the power fluid from about the stem 7 through the passageway 27 of the twin gate valve 22 to the semi-annular chamber 36 on the opposite side of the upper end of the motor section of the pump cylinder; the interior of the upper portion of this section or core being illustrated at 37 and in which is mounted the lowermost ball bearing 26, previously described, and below which may be installed any desired form of packing gland, as illustrated at 38; the exhaust from the chamber 19, of course, freely following the then opened communication to the space 41 intermediate of the pump cylinder and casing 1 through the passageways and ports 16, 14 and 50.

Just below the upper enlarged central portion or core 37 of the motor section of the pump cylinder 60 is an annular passageway 39 communicating with the passageway 36, so that power fluid now coursing this passageway 39 will be led to the under or lower end of the motor piston 31 and return it to its uppermost position or end of 65 its stroke, while the exhaust from the upper end thereof will be forced through the passageway 30 and ports 29 and 23 behind the twin gate valve 22, thence through the passageway 40 into the space 41 between the casing 1 and the pump cylinder. At the conclusion of the uppermost 70 stroke of the motor piston 31 carrying with it the stem 7, which latter is provided with a ring 42 fixed thereto similar to the ring 32 previously described and spaced therefrom the proper distance, the control valve 12 will be raised again

to the position illustrated in the drawings and initially described, ready for another cycle.

Now the pump pistons 43 for pumping oil and 44 for the care of gas, though it may at times handle some oil, being rigidly fixed to and carried by the depending outermost extension 58 of the motor piston 31, will obviously reciprocate with the action just described of the motor piston, and I shall now proceed to describe the flow of the pumped material, first through the 10 pistons.

Assuming as before stated that the valve 12 of the motor and the motor piston 31 are in their unfinished downward stroke, the pump pistons will be in like position, as shown, and the 15 oil remaining in the chamber 46, below the piston 43, will obviously be forced downwardly through the ball valves 47, (of which there may be any desired number circumferentially about the tubular connection 48 of the two pump pistons), and 20 outwardly into the space 41 between the pump cylinder and casing; while the gas in the similarly shaped and positioned chamber 49 below the piston 44 will be forced through the passageway 51 and the ball valve 52 and passageway 53 into 25 the bore 54 of the hollow valve stem 7. Here it must be noted that any air or gas thus liberated within the hollow stem 7 which leads to the standpipe 4, is entirely freed and avoids any obstruction to the operation of the pump, and 30 there is located at 55 a ball valve of predetermined pressure capacity under ordinary pumping conditions to function at say fifty pounds pressure, so that any oil which may have been drawn therein and creating such pressure may 35 escape through said valve.

At this time during the continued down stroke of the pump pistons 43 and 44, suction will be created within the chamber 56 above the piston 43 drawing oil through the ball valve 57 from the interior 59 of the tube 48, as communication of oil to said tube through the piston 44 is accomplished by the passages 60, see Figs. 8 and 9, simultaneously with like action in the chamber 61 externally of the tube 48 above the piston 44 which will draw gas through the passage 62, ball valve 63, and out of the central passageway 84 in the lower extremity of the pump, thus simultaneously filling these two chambers, 56 with oil, and 61 with gas, to be forced therefrom by the reverse action or upstroke of the pump pistons 43 and 44. Now when this upward stroke takes place, caused as is obvious by the reverse action of the motor piston previously described, the oil within the chamber 56 will be forced upwardly through the ball valves 64 in the stationary core 65 of the pump cylinder (the latter being provided with a suitable packing gland 66) thence upwardly through the passageways 67 into the chamber 68, through the interior 69 of 60 the tubular connection 70 between the stationary cores 65 and 37 into the chamber 71 within the core 37 and thence through the discharge port 72 into the space 41 intermediate of the pump cylinder and well casing and on up to the 65 surface of the well. This action of course is simultaneous with the discharge of the gas within the chamber 61 above the piston 44 which passes through the passageway 73 and ball valve 74 into the bore 54 of the hollow valve stem 7. 70

Obviously when the two pump pistons 43 and 44 are on their upward stroke discharging the contents of the chambers 56 and 61, just described, they will tend to form a vacuum in the chamber 46 beneath the piston 43, and also in

the chamber 49 beneath the piston 44, and which will result in the chamber 46 being filled by passage of the oil from the chamber 59 in the tubular connection 48 through the ball valve 78 5 and passageway 79 into said chamber, and, in respect to the chamber 49 the upward motion of the piston 44 will cause the gas or possibly some oil in the passageway 84 to be drawn through the ball valve 80 and passageway 81 10 into said chamber 49.

It will be noted that the intake of the passageway 84 is materially above the lower terminal of the pump suction pipe 82, and to which latter any length of pipe may be attached in keeping with the depth of oil being encountered.

It will also be noted that the annularly shaped motor piston 31 and the uppermost pump piston 43 form opposite ends of the cylinder 58 which reciprocates externally of the stationary core 65 20 and internally of the pump cylinder 2, thus forming ample length of piston for any desired number of piston rings suggested at 83, and that the connection of the pump cylinder to the packer O is accomplished by the foot member 88 in 25 which may be installed any desired number or form of packing means as suggested at 87; it being deemed non-essential throughout the drawings to illustrate the threaded connections of the various parts of the pump.

Having thus described my invention, what I claim and desire to secure by Letters Patent, is:

1. A deep well fluid pump comprising a casing, a cylinder within said casing, motor, oil pumping and gas pumping pistons within said cylinder and connected to operate in unison, a source of fluid power and intake and exhaust valves for directing said fluid power alternately to opposite ends of said motor piston, intake and exhaust valves for admitting oil to opposite ends of said oil pumping piston and discharging it therefrom to the surface of the well, intake and exhaust valves for admitting gas to opposite ends of said gas pumping piston and discharging it therefrom to the surface of the well independently of said oil discharge, the discharge from said gas piston extending through said other pistons.

2. A deep well fluid pump comprising a casing, a cylinder within said casing, motor, oil pumping and gas pumping pistons within said cylinder and connected to operate in unison, a source of fluid power, reciprocable valve means for controlling intake and exhaust valves for directing said fluid power alternately to opposite ends of said motor piston, intake and exhaust valves for admitting oil to opposite ends of said oil pumping piston and discharging it therefrom to the surface of the well, intake and exhaust valves for admitting gas to opposite ends of said gas pumping piston and discharging it therefrom to the surface of the well independently of said

gas pumping piston and discharging it therefrom to the surface of the well independently of said

oil discharge, the discharge from said gas piston extending axially of said other pistons and means for operating said reciprocable valve means.

3. A deep well fluid pump comprising a casing, a cylinder within said casing, a motor piston within said cylinder, a combined oil and gas pumping piston within said cylinder and operable in unison with said motor piston, a source of power fluid, intake and exhaust valves for directing said power fluid alternately to opposite ends of said motor piston, intake and exhaust valves for control of oil to one end of said combined piston and discharging it therefrom to the surface of the well, and intake and exhaust valves for control of gas to the opposite end of said combined piston whereby to pump gas separately from the well, and separate means to conduct the oil and gas to the surface of the well.

4. A double acting deep well fluid operated pump having a power piston and gas and fluid pumping pistons, all of said pistons being operable in unison, an outer casing, a cylinder concentric with and spaced from said casing and within which said pistons operate, a valve within the upper end of said cylinder for control of power fluid alternately to opposite ends of said power piston, means axially of all of said pistons to conduct gas from above the fluid in the well to the surface of the ground, valve means in said gas pumping piston to control the flow of gas therethrough to said axial means, and valve means in said fluid pumping piston to control the flow of fluid therethrough.

5. In a deep well fluid operated fluid and gas pump, an outer casing therefor, an inner pump cylinder, a fluid motor therein, an axial power fluid supply through said casing to operate said motor, fluid and gas pumping pistons in said cylinder and operated by and in unison with said motor, an independent gas discharge within said casing to receive the pumped gas and conduct it to the surface of the well, a standpipe within said casing for automatic pressure control of said fluid power supply, and valve means whereby the fluid pumped is discharged directly within said casing and carried independently of said pumped gas to the surface of the well.

6. A combined motor and pumping piston for fluid operated pumps comprising a hollow piston stem, a combined motor piston, fluid pumping piston and air or gas pumping piston fixed to said piston stem in spaced relation, valve controlled passageways through said fluid pumping piston for the alternate control of fluid passing therethrough, and valve controlled passageways in said air or gas piston for the control of air or gas passing therethrough to the interior of said hollow piston stem.

JULIUS PAUL. 60
